UNITED STATES PATENT OFFICE.

JOSEPH W. NORCROSS, OF BOSTON, MASSACHUSETTS.

IMPROVEMENT IN BLOCK-FRAMES.

Specification forming part of Letters Patent No. **179,126**, dated June 27, 1876; application filed March 18, 1876.

To all whom it may concern:

Be it known that I, JOSEPH W. NORCROSS, of the city of Boston, county of Suffolk, and State of Massachusetts, have invented certain new and useful Improvements in Block-Frames; and I hereby declare that the following is a clear, full, and exact description of the same, reference being had to the accompanying drawings, forming part of this specification.

Figure 1 is a perspective view of my improved block-frame, as made for a single block. Fig. 2 is an end view of my improved double block-frame. Fig. 3 is a partial section of the side frame and through *x x*. Fig. 4 is a partial section of the partition-frame in a double block through *y y*.

The object of this invention is to produce a block-frame of malleable iron, or any other suitable metal, that shall be stronger, cheaper, and better than block-frames as heretofore constructed; that shall present on all sides a smooth, rounded surface; shall have no straps or other projections liable to injure the masts, wood-work, or other portion of a vessel, and have all the advantages of a lignum-vitæ or egg-shaped block.

It consists in the peculiar arrangement of its parts and in the manner in which the same are cast or otherwise constructed, as will be more fully set forth hereinafter.

In the drawings, *a a* are the frames proper. They are cast in malleable iron or other suitable metal. All the surfaces, as, also, the edges, are perfectly smooth and rounded, so that no part can scratch or injure anything with which the block may come in contact. *b* is the rounded edge, perfectly smooth and turned in on the inner side, so as to form a recess, into part of which the sheave enters, so that the rounded edges *b b* form a guide for the rope and more effectually keep the same central on the sheave. *c* is the central partition-frame, provided with a rounded edge, as shown in Fig. 4. This partition is also used in triple or quadruple blocks. *d d* are the studs which separate the frames the proper distance. These studs are cast on each part of the frames, as shown in the

drawings, and through one of them the pin *E* passes, which, when riveted, secures the frames together. *E E* are pins or projections. They are usually part of either the central or one of the side frames of the block, and are cast in malleable iron or other suitable metal. These pins may be made of wrought-iron and cast into the frame, or in a single block. One side of the frame may be cast with the pins *E* and placed in the sand. A pattern like the other side may be placed on this, provided with holes for the pins to pass into, and, when rammed up and parted, the second side may be at once cast onto the pins, and the whole block-frame be so completed without riveting.

If required, the eye-hook may be placed, also, into the sand, and so the whole completed at one operation.

In a double block the pins are cast onto the central frame *c* projecting on each side, and may be cast into the side frames, as before described, or be riveted to the same.

f f are the bosses in which the sheave-spindle is secured. They are, therefore, cast with the hole *g* to receive the spindle. The bosses *f f* project above the inner surface of the block-frames, and thus prevent the friction caused by the sheave when in contact with the sides. The sheaves will, therefore, turn with the least possible friction.

When cast of malleable iron and properly annealed, these block-frames are superior to the best lignum-vitæ blocks. They are strong, light, cheap, and durable. They have no straps or other projecting parts. They can injure no part of a vessel, and will pass freely along and between ropes or sails without injury.

Having thus described my invention, I claim as new and desire to secure by Letters Patent—

1. In a cast-metal block-frame, the frame *a* proper, having the rounded edge *b*, forming a rounded corner on the outside and a recess on the inside of the frame, as and for the purpose set forth.

2. The combination, with the frames *a a*, provided with the rounded edges, of the pins

E E, cast onto one part of the frame, and riveted to the other, substantially as and for the purpose set forth.

3. The method, substantially as herein described, of casting the outer frame onto the inner frame or to the other outer frame, and around the projecting pins, as and for

the purpose set forth, so as to produce a complete single or double block frame without riveting.

JOSEPH W. NORCROSS.
